DESIGN FOR A BURIAL CASE HANDLE

William F. Flasche, Lakewood, Ohio, assignor to
The Dickey-Grabler Company, Cleveland,
Ohio, a corporation of Ohio

Application March 16, 1936, Serial No. 61,653

Term of patent 7 years

To all whom it may concern:

Be it known that I, William F. Flasche, a citizen of the United States, residing at Lakewood, in the county of Cuyahoga and State of Ohio, have invented a new, original, and ornamental Design for Burial Case Handles, of which the following is a specification, reference being had to the accompanying drawing, forming part thereof, and wherein Fig. 1 is a front elevation, and Fig. 2 an end elevation of a burial case handle showing my new design with the part illustrated by dotted lines in Fig. 1 omitted.

I claim:

The ornamental design for a burial case handle, as shown.

WILLIAM F. FLASCHE.
